UNITED STATES PATENT OFFICE

2,667,830

ROTARY CAN END MARKER

Ed Laxo, Oakland, Calif., assignor to Atlas Imperial Diesel Engine Co., Oakland, Calif., a corporation of Delaware

Application October 18, 1948, Serial No. 55,129

6 Claims. (Cl. 101—4)

1

This invention relates to a can end marker for stamping indicia upon the ends of cans.

It is a common cannery practice to feed can bodies and can ends to a double seamer for joining the ends to the bodies, and along with such operation to mark the can ends with indicia indicating, for example, the date of canning, the type of product canned, etc. Double seamers employed for this purpose operate at a very high speed, and it is essential that the can ends be fed thereto at high speed. It is therefore important to provide an end marker capable of marking can ends at high speed, and in exact synchronization with the operation of a can end feed and a double seamer.

It is an object of this invention to provide an improved form of end marker for can ends.

It is a further object of the invention to provide an end marker for can ends which is capable of operation at high speeds.

It is a still further object of the invention to provide an end marker for can ends which is readily adjustable to adapt it to can ends of varying thickness.

These and other objects of the invention will be apparent from the ensuing description and the appended claims.

One form which the invention may assume is exemplified in the following description and illustrated by way of example in the accompanying drawings in which:

Fig. 1 is a plan view of the end marking mechanism showing it in conjunction with a can end feed and a can body feed.

Fig. 2 is a vertical section taken along the line 2—2 of Fig. 1.

Figs. 3 and 4 are sections taken along the lines 3—3 and 4—4, respectively, of Fig. 2, showing the manner in which the end marker countershaft is secured to the drive mechanism.

Fig. 5 is a plan view similar to that of Fig. 1 but on a larger scale and showing only the end marker.

Fig. 6 is a section taken along the line 6—6 of Fig. 5, showing a release and adjustment mechanism.

Fig. 7 is a section taken along the line 7—7 of Fig. 8, showing the means for pivoting the end marker and for aligning it in operative and inoperative positions.

Fig. 8 is a section taken along the line 8—8 of Fig. 2, showing the end marker in end elevation and with the dies in one position.

Fig. 9 is a view similar to that of Fig. 8, but showing the dies in another position.

2

Fig. 10 is a section taken along the line 10—10 of Fig. 2, showing the driving connection between the upper and lower marker heads.

Fig. 11 is a vertical section through one of the die magazines, showing the manner in which the dies are secured thereto.

Fig. 12 is a section taken along the line 12—12 of Fig. 8, showing the means of locking the die magazines in predetermined rotary position.

Referring now to the drawings, and more particularly to Fig. 1, there is shown an end marker 10 associated with a can end feed 11 and a can body feed 12. Can ends 13 are fed by a turret 14 from the end feed to a marking station designated 15 as A (see Fig. 2), where they are marked by the end marker; thence by means of a turret 15 in alignment with can bodies 16 to a double seamer (not shown) of any suitable construction, but preferably of the type described in my copending application Ser. No. 55,130, filed October 18, 1948, entitled "Double Seamer," now U. S. Patent No. 2,540,001.

Referring now to Fig. 2, a main drive shaft 17 is provided having secured thereto a gear 18 for driving the end feed by means (not shown) such as described and illustrated in my copending application Ser. No. 55,128, filed October 18, 1948, entitled "Can End Feed Mechanism," now abandoned. The drive shaft 17 is secured at its upper end to the turret 14, causing rotation of the turret. A gear train consisting of a gear 25 secured to the drive shaft 17 and the gears 26, 27, 28 and 29 are disposed in a gear case 30 and drive a countershaft 31 which in turn drives a bevel gear 32. The driving connection between the gear 29 and shaft 31 is formed as follows, reference being had to Figs. 3 and 4 in addition to Fig. 2: As shown, the gear 29 is integral with a hub 33 which is keyed to a collar 34 by means of set screws 35. The collar 34 is keyed to the shaft 31 by a key 36 and, as will be seen, the collar 34 is split and is provided with screws 37 for clamping the shaft 31 and collar 34 in adjusted position. This manner of interconnecting the gear 29 and the countershaft 31 permits rotation of the shaft 31 relatively to the gear 29, and therefore the main drive shaft 17, merely by loosening the clamping screws 37, tightening one of the set screws 35 and loosening the other and then tightening the clamping screws 37. The purpose of such adjustable features is to time the end marking mechanism with the end feed mechanism as is more fully explained hereinafter.

Upper and lower marker heads 45 and 46 are mounted on a marker frame 47, the lower head

46 being integral therewith and the upper head 45 being pivotally supported upon a shaft 48 by means of arms 49. The upper head also receives support, and is adjustable in height to accommodate can ends of different thicknesses, by means of a release mechanism generally designated as 50 and shown most clearly in Fig. 6. The release mechanism 50 is explained in detail hereinafter.

The whole marker assembly is rotatable in the machine frame 9 by means of a circular flange 55 clamped to the frame 9 by means of a clamping ring 56 and screws 57. The flange 55, as shown in Fig. 7, has two V-shaped recesses 58 formed therein approximately 90° apart, and a key or latch member 59 is provided, being slidably disposed in a boss 60 and urged inwardly by a coil spring 61 into engagement with one or the other of the recesses 58. A cap 62 secured to the boss by set screw 63 is also provided.

It will thus be seen that the end marker may be rotated so as to be out of the way of the rest of the machine whenever such is necessary for inspection or repair. It will also be noted, that by means of the key 59 and slots 58, the marker, whenever returned to operative position, is always precisely aligned with the end feed turret 14.

Each of the marker heads comprises a crank-shaft 64 rotatable in a sleeve 67. The lower crankshaft 64 is driven by the bevel gear 32 and a bevel gear 68. The upper crankshaft 64 is driven by a gear train consisting of bevel gears 32 and 68, gear 75, idler gears 76 and 77 (see Fig. 10), secured to eccentric shafts 78 and 79, having squared ends 80, and a gear 81. The gear 81 is drivingly connected to the upper crankshaft 64 by means of a split hub 82 keyed to the shaft 64 by set screws 83, which are clamped in adjusted position by means of a clamping screw 84. It will thus be apparent that, by loosening the clamping screw 84 and loosening one of the set screws 83 while tightening the other, the upper crankshaft 64 may be rotated relatively to the lower crankshaft 65, and when adjusted to the desired position may be clamped therein by means of the clamping screw 84. Thus, provision is made for adjusting one of the upper marker heads 45 relatively to the lower marker head 46 so as to synchronize the two accurately.

A die magazine 90 is provided for each marker head, such magazine being rotatable on a stub shaft 91 integral with a crank 92 secured to the crankshaft 64, the die magazine being clamped in place by means of a clamping plate 93 and screw 94. Each die magazine 90 is provided with a lever arm 95 integral therewith and pivotally connected at 96 to one end of a link 97, the other end of which is pivotally and eccentrically connected to an eccentric pin 98 (see Fig. 5) having a squared end 100 by which it may be adjusted, said pin being carried by a bracket 101.

As shown in Figs. 8 and 11, each die magazine 90 is also provided with three radial recesses 110, spaced 120° apart and in which dies 111 are seated. Each recess 110 is provided with steel balls 112 and coil springs 113 as shown to provide a snap type seat for the die. The dies 111 are of conventional construction and require no further elaboration here except to note that, of course, the dies in one of the marker heads will be male dies whereas those in the other head will be female dies. It will also be noted that the die magazine is provided with three notches 114, also spaced 120° apart, and with a tapered, knurled knob 115, such knob being rotatable and

on an eccentric shaft 116. It is thus apparent that, when it is desired to use one of the dies 111 and its corresponding die on the other head, the knob 115 will be rotated so as to unlatch the die magazine, the latter will be rotated on the stub shaft 91 until the selected notch 114 is brought into alignment with the knob 115, and then the knob 115 will be rotated until it is firmly seated in the notch so as to lock the die magazine in adjusted position.

Referring now to Fig. 6, the above mentioned release mechanism 50 is shown as comprising a hollow screw 120 having a flat head 121 and in threaded engagement at 122 with the end marker frame. A rod 123 is received within the screw 120 and within a recess 124 formed in the upper marker 45, the lower end of the rod being in threaded engagement at 126 with the marker frame and being clamped in place by means of a set screw 127. A coil spring 128 is provided, which encircles the rod 123 and is compressed and adjusted by means of nuts 129.

It will be apparent that, in the event of jamming of one or more can ends between the marking dies 111, resulting in undue pressure upon the upper marker head 45, that the latter will be unseated from screw 120 against the compression of spring 128, thus preventing damage to the dies and to the other parts of the end marker.

In operation the end marker functions as follows: It is driven in timed relationship with the can body feed 12, the can end feed 11 and the double seamer by means of the drive shaft 17 and the gear train and other driving means described hereinabove. Previously, of course, the marker heads 45 and 46 will be brought into proper, timed relationship with each other and with other parts of the machine by means described hereinabove. As the crankshafts 64 rotate, the die magazines 90 and therefore the dies 111 will be constrained to follow an ovate path because of the crank connection to the crankshafts and also because of the link and lever connections to the frame brackets 101. As is apparent from Figs. 8 and 9, the fixed axes about which links 97 pivot are disposed in a plane perpendicular to the path of travel of the can ends to be marked, said plane being disposed on the sides of the crankshafts remote from the direction from which the can ends are fed to the dies, whereby the dies travel along ovate closed paths whose major axes intersect to form an angle facing in the direction from which the can ends are fed to the dies. A fine adjustment of the path of travel of each die is possible by reason of the eccentric pin 98. Thus, by rotating this pin, the lever 95 is adjusted as to its rotary position i. e., moved toward or away from bracket 101, and thus both the lever and die holder are rotatably shifted about the axis of rotation of the die holder. This obviously alters the path of travel of each die. This adjustment is made until the paths of travel of the upper and lower dies become tangent when the dies are in vertical alignment as shown in Fig. 9. At the instant of impact and of marking the can end, the dies 111 are traveling at the same speed, in the same direction and in tangent paths. Thus, no hammering or pounding effect is obtained, the path of travel is continuous, and very high speed operation is possible over long periods of time.

It is thus apparent that an end marking machine has been provided which is operable to mark can ends and the like accurately and

dependably and at high speeds. Several improved features are embodied in the machine, such as the adjustable driving connection between the main drive shaft 17 and the counter-shaft 31 which permits rotation of the latter relatively to the former for timing the end marker with the end feed. Also, provision is made for rotating the entire marking mechanism into inoperative position for purposes of inspection and repair, and for ensuring return to exact operative position, in precise alignment with the end marking station. Further, separate and independent means of rotating one of the crankshafts relatively to the other is provided, so as to ensure accurate timing of the two marker heads. Also, provision is made for adjusting the spacing of the upper and lower marker heads to accommodate can ends of varying thickness, and means is provided for fine and accurate adjustment of the path of travel of each of the die magazines so as to ensure tangent contact of the dies at the instant of marking. Further, certain safety features have been provided as explained hereinabove and a die magazine has been provided which allows a rapid change of dies.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. Apparatus of the class described, comprising a marking station, a pair of crankshafts disposed one on either side of the marking station, means for rotating the crankshafts in unison, a crank for each crank shaft, means supporting a die pendulously on each crank for rotation thereabout, a lever fixedly secured at one end to said die, a link one end of which is pivotally connected to the end of the lever, the other end of said link being pivotally mounted about a fixed axis, the lever and link being so arranged with respect to the orbit of the crank that they cyclically vary the angle formed between the crank and means pendulously supporting the die, whereby the dies are caused to traverse closed ovate paths of travel tangent to one another at said marking station.

2. Apparatus of the class described, comprising a marking station, a pair of crankshafts disposed one on either side of the marking station, means for rotating the crankshafts in unison, a crank for each crank shaft, a die holder carrying a plurality of dies supporting said dies pendulously on each crank for printing engagement, means for selecting a die on each holder for cooperating printing engagement, a lever fixedly secured at one end to said die, a link one end of which is pivotally connected to the end of the lever, the other end of said link being pivotally mounted about a fixed axis, the lever and link being so arranged with respect to the orbit of the crank that they cyclically vary the angle formed between the crank and said die holder, whereby the dies are caused to traverse closed paths of travel tangent to one another at said marking station.

3. Apparatus of the class described, comprising a marking station, a pair of crankshafts disposed one on either side of the marking station, means for rotating the crankshafts in unison, a crank for each crankshaft, a die rotatable on each crank, means supporting said die pendu-

lously on each crank for rotation thereabout, a lever fixedly secured, at one end to said die, a link one end of which is pivotally connected to the end of the lever, the other end of said link being pivotally mounted about a fixed axis, the lever and link being so arranged with respect to the orbit of the crank that they cyclically vary the angle formed between the crank and the means pendulously supporting the die, whereby the dies are caused to traverse closed ovate paths of travel tangent to one another at said marking station.

4. Apparatus of the class described, comprising means for conveying a series of members to be marked along a fixed path, a pair of crankshafts disposed one on either side of the fixed path, means for rotating the crankshafts in unison, a crank for each crankshaft, a die rotatable on each crank, means supporting said die pendulously on each crank for rotation thereabout, a lever for each die, each lever being fixedly secured at one end to its die, a link for each lever, each link being pivotally connected at one end to the free end of its lever and pivotally mounted at its opposite end for pivotal movement about a fixed axis, the fixed axes about which the links pivot being disposed in a plane perpendicular to the path of travel of the members to be marked and spaced from and disposed on the sides of the crankshafts remote from the direction from which the members to be marked are fed to the dies, whereby the dies travel along ovate closed paths whose major axes intersect to form an acute angle facing in the direction from which the members are fed to the dies.

35 5. Apparatus of the class described, comprising means for conveying a series of members to be marked along a fixed path, a pair of crankshafts disposed one on either side of the fixed path, means for rotating the crankshafts in unison, a crank for each crankshaft, a die rotatable on each crank, means supporting said die pendulously on each crank for rotation thereabout, means for causing the dies to traverse over a path of travel comprising a lever for each die, each lever being fixedly secured at one end to its die, a link for each lever pivotally connected at one end to the free end of said lever, bodily stationary eccentric means pivotally connected to the other ends of the links and operable when rotatably adjusted to shift the axis about which said other ends of said links pivot to vary the paths of travel of the dies, the fixed axes about which the links pivot being disposed in a plane perpendicular to the path of travel of the members to be marked and spaced from and disposed on the sides of the crankshafts remote from the direction from which the members are fed toward the dies, whereby the dies travel along ovate closed paths whose major axes intersect to form an acute angle facing in the direction from which the members to be marked are fed toward the dies.

6. Apparatus of the class described, comprising means for conveying a series of members to be marked along a fixed path, a pair of crankshafts disposed one on either side of the fixed path, means for rotating the crankshafts in unison, a crank for each crankshaft, a die holder carrying a plurality of dies supporting said dies pendulously on each crank for printing engagement, means for selecting a die on each holder for cooperating printing engagement, a lever for each die holder, means for releasably securing each lever at one end to its die holder releasable to permit each holder to be rotated relative to its lever to operatively present a different die for

marking purposes, a link for each lever, each link being pivotally connected at one end to the free end of its lever and pivotally mounted at its opposite end for pivotal movement about a fixed axis, the fixed axes about which the links pivot being disposed in a plane perpendicular to the path of travel of the members to be marked and spaced from and disposed on the sides of the crankshafts remote from the direction from which the members are fed toward the dies, 10 whereby the dies travel along ovate closed paths whose major axes intersect to form an acute angle facing in the direction from which the members are fed toward the dies.
